DOOR LATCH MECHANISM

Fred Kaiser, Brooklyn, N. Y.

Original application July 11, 1939, Serial No. 283,749. Divided and this application December 6, 1939, Serial No. 307,763

4 Claims. (Cl. 292—165)

This invention relates to improvements in door latch mechanism; this application being a division of subject matter disclosed in my copending application Serial No. 283,749, filed July 11, 1939, which has matured into Patent No. 2,188,149 of Jan. 23, 1940.

This invention has for an object to provide a novel improved latch mechanism of the kind which is contained within a tubular or cylindrical casing mortised into a door body; said latch mechanism being selectively manipulatable by the spindle means of interior and exterior knobs which are disposed respectively at the inner and outer sides of the door served by the latch mechanism.

This invention has for another object to provide improvements in the latching mechanism, whereby the various movable parts thereof are so spring balanced and controlled that operation thereof by the knob spindle means is smoothly and easily attained with a minimum of resistance, and whereby the latch mechanism is more efficiently yieldably supported in latching position, as well as quickly returned to latching position after releasing manipulation.

Other objects of this invention, not at this time more particularly enumerated, will be understood from the following detailed description of the same.

An illustrative embodiment of the invention is shown in the accompanying drawing, in which:

Fig. 1 is a fragmentary outside face view of a door equipped with the novel latch mechanism of this invention; Fig. 2 is a vertical cross section, taken on line 2—2 in Fig. 1; Fig. 3 is a longitudinal section taken on line 3—3 in Fig. 2, but drawn on an enlarged scale, this view showing the normal projected position of the door latch; and Fig. 4 is a view similar to that of Fig. 3, but showing the door latch retracted.

Similar characters of references are employed in the above described views, to indicate corresponding parts.

Referring to the drawing, the reference character 10 indicates a door to be served by the novel latch mechanism. Mounted in a mortised opening 11, extending inwardly into the door body from its free end, is a cylindrical casing. This casing is longitudinally divided into two half sections 12 and 13 which are suitably secured together, one of which, as e. g. the section 12, is provided with an anchoring plate or flange portion 14, adapted to be countersunk in the door body edge and secured thereto by screws (not shown) in the usual manner, thus retaining the

casing in operative assembled relation to said door body. Said anchoring plate or flange portion 14 is provided with an opening 15 aligned with the interior of the casing, and through which the chamfered latch nosing 16 of the latch mechanism is normally outwardly projected. Said latch nosing 16 is carried by a latch plate 17, which is suitably slidably supported in the forward interior portion of the casing. Said latch plate 17 is formed with laterally spaced 10 rearwardly directed longitudinal legs 18 which straddle a stationary abutment member 19, which is preferably formed as an integral part of the casing section 12. Extending rearwardly from one of the latch plate legs 18 is a tail-piece 20 15 having at its extremity an upstanding retractor lug 21. Said latch plate 17 is yieldably urged forwardly to latch nosing projecting position by a compression spring 22 engaged between the same and said abutment member 19; said latch 20 plate having a keeper lug 23 for seating the end of the spring 22 which engages the same.

The casing sections 12—13 are provided with laterally aligned transverse bearing portions 24 in which are respectively journaled the opposite 25 ends of the journal hub 25 of a rotary cam piece which provides oppositely and radially extending cam arms 26.

Longitudinally slidable in the rearward interior portion of the casing is a pull-plate 27 having rearwardly extending laterally spaced legs 28 adapted to straddle said hub 25 of the cam piece. Said legs 28 are each provided, adjacent their extremities, with offset retractor lugs 29 respectively engageable by the respective cam arms 26 of said cam piece. At its forward end, said pull-plate 27 is provided with a longitudinally extending offset pull-tongue 30. This pull-tongue is provided, adjacent to its free end, with an upstanding thrust lug 31. The interior of the 30 casing section 12 is suitably formed to provide a guiding slideway 32, for said pull-tongue 30. Pivotally mounted on a suitably located fulcrum stud 33, with which said casing section 12 is provided, is a transversely disposed latch plate actuating lever 34 having a thrust nosing 35 at its free end to operatively engage the retractor lug 21 of the latch plate tail-piece 20; said lever being operatively engaged, at a point intermediate 45 its fulcrum and free end, by said pull-plate thrust lug 31, whereby a minimum actuating movement of said pull-plate is compounded by and transmitted through said lever 34 to effect a maximum latch plate movement adequate to fully re- 50 55

tract the latch-nosing 16 when the latch mechanism is actuated.

The pull-plate 27 is yieldably maintained in forwardly moved normal initial position by means 5 of a pair of compression springs 36, which are positioned against the rearward end wall of the casing, with their forward ends engaged respectively with the ends of the respective legs 28 of said pull-plate 27; the latter parts having seating bosses 37 to engage and hold said springs in operative relation thereto. By reason of the provision of said springs 36 to directly thrust upon and forwardly move said pull-plate 27, a yieldable forwardly thrusting force auxiliary to that 10 exercised by the latch-plate spring 22 is furnished, whereby not only is a better balancing of the combined action of the moving parts of the latch mechanism attained, but the use of a less stiff and more smoothly operating latch plate 15 spring is possible, and consequently a smoother and easier action of the latch mechanism as a whole is obtained.

The means for manipulating the above described latch mechanism comprises, a knob spindle means 38 of substantially polygonal cross sectional shape to extend through the correspondingly shaped axial opening 39 of the rotatable cam piece 25—26 from one side of the door to the other. An exterior knob 40 is operatively connected with the knob spindle means 38 at one end thereof, and an interior knob 40' is operatively connected with said knob spindle means at the other end thereof.

The novel latch mechanism is optionally actuated by turning the spindle means 38 by either the exterior knob 40 or the interior knob 40', as the case may be. Turning of the spindle means 38 operates to rotate the cam-piece 25 to engage one or the other of its cam arms 26 (as 40 the case may be) with a corresponding retractor lug 29 of the pull-plate 27, whereby the latter is retracted against the thrust of the springs 36. The rearward movement of said pull plate 27 moves the thrust lug 31 against the lever 34, 45 thereby swinging the latter rearward so as produce, through the engagement of the lever nosing 35 with the retractor lug 21 of the latch plate 17, a relatively greater rearward sliding movement of said latch plate, whereby the latch 50 nose 16 is retracted to door releasing position.

Owing to the form of the pull-plate 27 having the spaced legs 28 which straddle the cam-piece 25, and the provision of the two compression springs 36 which respectively thrustingly bear 55 against the extremities of the respective pull-plate legs 28, a straight line and smoothly balanced movement of the pull-plate is assured, so that canting or cocking of the latter with rubbing and resultant frictional obstruction to free 60 and easy movement thereof is avoided. As a consequence of this the relative movements of the latch mechanism parts are smoothly and easily attained with a minimum of resistance, so that the latch mechanism works with a so-called 65 "soft" action, and so as to assure efficient action of the same in its door closing and latching operation.

Since changes could be made in the above described latch mechanism, as well as in the details 70 of the construction thereof, without departing from the scope of my invention as defined in the following claims, I do not intend to limit the invention to the exact arrangement and construction of the devices and parts as hereinabove described and as shown in the drawings, said de-

scription and showing being intended to be interpreted as illustrative and not in a limiting sense.

I claim:

1. In door latch mechanism, a cylindrical casing adapted to be mortised into the free marginal edge portion of a door to be served by said latch mechanism, a cam piece rotatively mounted across said casing for operative engagement by door knob spindle means, a latch plate longitudinally slidable in said casing and provided with a latch nose for projection from the outer end of said casing, spring means for yieldably retaining said latch plate in latch nose projecting position, a longitudinally slidable pull plate behind and in longitudinal alignment with said latch plate, said pull plate having means engageable by said cam piece for retracting the same upon operation of the latter, said casing having a fixed abutment intermediate said latch plate and pull plate to support said latch plate projecting spring means, independent spring means for yieldably retaining said pull plate in forwardly moved normal position, and means intermediate said pull plate and said latch plate for transmitting operative movement of the former to the latter.

2. In door latch mechanism, a cylindrical casing adapted to be mortised into the free marginal edge portion of a door to be served by said latch mechanism, a cam piece rotatively mounted across said casing for operative engagement by door knob spindle means, a latch plate longitudinally slidable in said casing and provided with a latch nose for projection from the outer end of said casing, spring means for yieldably retaining said latch plate in latch nose projecting position, a longitudinally slidable pull plate behind and in longitudinal alignment with said latch plate, said pull plate having means engageable by said cam piece for retracting the same upon operation of the latter, said casing having a fixed abutment intermediate said latch plate and pull plate to support said latch plate projecting spring means, independent spring means for yieldably retaining said pull plate in forwardly moved normal position, and means intermediate said pull plate and said latch plate for transmitting operative movement of the former to the latter, said latter means comprising a pivoted lever arm, retractor means on said latch plate engageable by the free end portion of said lever arm, and means carried by said pull plate to engage said lever arm intermediate its pivoted and outer free end portions.

3. In a door latch mechanism, a cylindrical casing adapted to be mortised into the free marginal edge portion of a door to be served by said latch mechanism, a cam-piece rotatively mounted across said casing for operative engagement by door knob spindle means, a spring projected latch plate longitudinally slidable in said casing and provided with a latch nose for projection from the outer end of said casing, a longitudinally slidable pull-plate behind and in longitudinal alignment with said latch plate, said pull plate having spaced rearwardly extending legs to straddle said cam-piece, each said leg having means engageable by the latter whereby to impart retractive movement to said pull-plate, a compression spring footed against the rearward end of the casing for thrustingly engaging each said leg for yieldably retaining said pull-plate in forwardly moved normal position, and means in-

termmediate said pull-plate and said latch plate for transmitting movements of the former to the latter.

4. In a door latch mechanism, a cylindrical casing adapted to be mortised into the free marginal edge portion of a door to be served by said latch mechanism, a cam-piece rotatively mounted across said casing for operative engagement by door knob spindle means, a spring projected latch plate longitudinally slidable in said casing and provided with a latch nose for projection from the outer end of said casing, a longitudinally slidable pull-plate behind and in longitudinal alignment with said latch plate, said pull

means engageable by the latter whereby to impart retractive movement to said pull-plate, a compression spring footed against the rearward end of the casing for thrustingly engaging each said leg for yieldably retaining said pull-plate in forwardly moved normal position, and means intermediate said pull-plate and said latch plate for transmitting movements of the former to the latter, said latter means comprising a pivoted lever arm, a retractor means on said latch plate engageable by the free end portion of said lever arm, and means carried by said pull-plate to engage said lever arm intermediate its pivoted and outer free end portions. 5

FRED KAISER. 15

10 15 plate having spaced rearwardly extending legs to straddle said cam-piece, each said leg having
